UNITED STATES PATENT OFFICE.

ANTOINE DIAT, DIT DIAZ, OF BRUSSELS, BELGIUM.

MEANS FOR GLAZING WINDOWS.

SPECIFICATION forming part of Letters Patent No. 734,829, dated July 28, 1903.

Application filed December 1, 1902. Serial No. 133,489. (No model.)

To all whom it may concern:

Be it known that I, ANTOINE DIAT, DIT DIAZ, a citizen of the French Republic, and a resident of Brussels, Belgium, have invented a certain new and useful Improved Means for Glazing Windows and the Like, of which the following is a specification.

The object of this invention is to provide means of glazing windows or the like with very thick glass and especially glass strengthened by metal to form an incombustible window.

The object of this means is to avoid the disastrous fires in warehouses, workshops, spinning-mills, and other buildings, by permitting the use of wood and iron to be avoided in the frames hitherto used, at least inside the buildings, as wood is capable of being burned and iron will warp beneath the action of the heat, and thus break the glass.

In the accompanying drawings, Figure 1 shows a front elevation of a sash made according to the present invention and comprising iron strips upon the outside. The left half of this figure shows an outside view of the sash, while the other half shows an inside view of same. Fig. 2 shows a detail of Fig. 1. Fig. 3 is a section on A A of Fig. 1. Fig. 4 is a section on B B of Fig. 1. Fig. 5 is a section on C C of Fig. 1. Fig. 6 is a section on D D of Fig. 1. Fig. 7 is a section on E E of Fig. 1. Fig. 8 is a section on F F of Fig. 1. Fig. 9 is a section on G G of Fig. 1. Fig. 10 is a section on H H of Fig. 1. Fig. 11 is a detail. Fig. 12 is a plan view of the stop shown in Fig. 2. Fig. 13 is an inside view of a sash made according to this invention, but without frame-irons. Fig. 14 is a section on I I of Fig. 13. Fig. 15 is a section on J J of Fig. 13. Fig. 16 is a section on K K of Fig. 13. Fig. 17 is a section on L L of Fig. 13. Fig. 18 is a section on M M of Fig. 13. Fig. 19 is a section on N N of Fig. 13. Fig. 20 is a section on O O of Fig. 13.

In the species shown in Figs. 1 to 12 each sheet of glass *a* is placed behind a frame *b*, formed of iron strips, and they are held between this frame and stops *c*, made of copper, held fast by means of screws of the same metal. In order to prevent any passage of

air and water, bands *e* and stops of asbestos are inserted between the frame-irons, the stops, and the sheets of glass, and thus form a tight joint. When two panes are superposed in the same sash, they are arranged so as to overlap each other, as will be seen from Fig. 9. By this means a perfect tightness is obtained, and the use of any iron toward the interior of buildings is avoided, and consequently breakage of glass in case of fire. The overlapping of two superposed panes in a same sash necessitates the use of a packing-strip *g* beneath the T-irons constituting the lower sash-frames.

In the species shown in Figs. 13 to 20 the glass is placed in a recess *h*, made in the brick-work, and is held therein by stops *c*, bolts *i*, one end whereof is held in the said brick-work, and nuts *j* with washers *f* and strips of asbestos *e* inserted therebetween. A layer of cement *k* is inserted between the outer asbestos washer and the brickwork. At its lower end the glass bears, by means of a strip of asbestos, upon the brickwork, Fig. 20. T-irons *l* are arranged horizontally and vertically in order to assure the fixing of the panes of a same sash, and the said panes are held against these irons *l* by means of stops *c*, similar to those already mentioned, and with the insertion of washers and strips of asbestos, Figs. 17, 18, and 19. In all cases the panes are filled around with asbestos, putty, or plastic substance *x x*.

Having now fully described my invention, what I claim, and desire to secure by Letters Patent, is—

In combination, an outer sash of rolled iron, a glass window-pane, adapted to fit said sash, copper or soft-iron stops and screws engaging said sash and pane to support the latter, strips of asbestos between said sash and pane and washers of asbestos between said stops and pane.

In testimony whereof I have hereunto set my hand in presence of two witnesses.

ANTOINE DIAT, DIT DIAZ.
